UNITED STATES PATENT OFFICE.

CHARLES H. BOMBARDIE, OF SOUTH BEND, INDIANA, ASSIGNOR TO WIREBOUNDS
PATENTS COMPANY, OF KITTERY, MAINE, A CORPORATION OF MAINE.

WIRE-BOUND-BOX MACHINE.

1,371,599.

Specification of Letters Patent. Patented Mar. 15, 1921.

Application filed December 29, 1916. Serial No. 139,509.

To all whom it may concern:

Be it known that I, CHARLES H. BOMBARDIE, a citizen of the United States, and resident of South Bend, county of St. Joseph, State of Indiana, have invented an Improvement in Wire - Bound - Box Machines, of which the following description, in connection with the accompanying drawings, is a specification, like characters on 10 the drawings representing like parts.

In the operation of machines for use in making wire-bound boxes, box blanks or sections, it is desirable to fasten together the box material, *e. g.* cleats and side material, and the binding wires thereto in desired relation to the edges of the work or otherwise and to avoid fastenings at the box joints. Among other objects my invention is intended to provide a machine of the 20 general class referred to which, acting continuously, will position the successive fastening devices in any desired relation. For instance, in producing a wirebound box by progressively stapling binding wire to assembled cleats and side material it is desirable to place those staples nearest the box corners in definite relation thereto and if the box is of the type known as a crate the spacing of the staples throughout the side of 30 the box will be irregular because of the use of spaced slats.

My invention will be best understood by the description of an illustrative embodiment thereof shown in the accompanying drawings wherein—

Figure 1 is a side elevation of one end of a box blank machine embodying my invention.

Fig. 2 is a section on the line 2—2 of 40 Fig. 1.

Box blank machines in general consist of a stapler head or battery of staple-forming and driving mechanisms and a work holder, the two being moved relatively step by step 45 so that the staples will be driven at various points along the work dependent upon the length of the steps.

In the present embodiment of the invention I show (Fig. 2) a machine embodying a fixed stapler head and a movable work holder. The stapler head is mounted in suitable frame 1, as shown, having the fixed cross-bar 3 and a reciprocating cross-head 5, which together carry the stapling mechanisms 7 shown diagrammatically in Fig. 2.

The cross-head 5 is reciprocated by pitman 9 and eccentrics 11 on the main drive shaft 13, and each time that it descends a staple is driven into the work beneath the cross-bar 3. In Fig. 1 the eccentric 11 has been 60 broken away to more clearly show the structure in which my invention more particularly resides.

Referring now more particularly to Fig. 1, the work is moved beneath the stapler 65 head on a work holder comprising cleat receiving chains 15, trained over sheaves 17 and supported on the longitudinal channel bars 19. But one set of sheaves is shown in the figure as the general construction of 70 mechanism so far described is well known in the art and no difficulty will be found in understanding the operation of the parts mentioned.

In the example of the invention illustrated 75 the chains are advanced step by step by a reciprocable driver arranged to impart motion on movement in one direction. Such a driver is exemplified by the pawl lever 21 coöperating with ratchet wheel 23 on the 80 axle of the sheaves 17. The pawl lever 21 is moved by a suitable fixed throw actuator such as the lever 25 moved by eccentric 27 on the main shaft and a connection is provided between the levers 25 and 21 permitting lost motion so that the working stroke of the pawl lever 21 may be varied. In the present instance this connection is a telescopic one and is so constructed that the lever 25 in its normal stroke positions the 85 driver at one extreme of its movement. To effect this a rod 29 extends from pawl lever 21 and may be guided in suitable bearings 31 on the frame of the machine. Slidable upon this rod is a block 33 to which the lever 90 25 is connected and a collar 35 is attached to the rod and coöperates with this block, as shown in Fig. 1, so as to draw the rod to the right in the clockwise stroke of the actuator lever. On the counter clockwise or 95 driving stroke of the lever 25 the block 33 would slide freely to the left on rod 29 were it not for force-transferring means next to be described which act to transmit more or less of the motion of the actuator lever 100 25 to the pawl-carrying lever 21.

In the embodiment of the invention illustrated the force-transferring means takes the form of an abutment 37 on the rod 29 and a coöperating, oppositely disposed abut- 110

ment on the sliding block 33. Intermediary force-transferring members are presented between these abutments to delimit the amount of lost motion of the block on the 5 rod.

In Fig. 1 a short headed rod or pin 41 mounted in a carrier, here shown as a wheel 43, is in position between the two abutments 37 and 39 and it is apparent that as the abutment 39 moves to the left it will push to the left the pin 41 and through it the abutment 37 and so move the pawl carrying lever 21. The stroke of the block 33 is designed to carry the abutment 39 into close proximity to the face of wheel 43 and therefore the movement of the pin 41 and consequently of the pawl carrying lever 21 will depend upon the projecting length of the pin. For example, if the pin 41^a shown at the lower part of the wheel in Fig. 1 were in position between the abutments instead of the pin 41, it is obvious that a much shorter left hand stroke would be imparted to the rod 29 and consequently the ratchet wheel 23 would be moved through fewer teeth and a shorter step imparted to the work carrier 15. In other words, the rod and sleeve with their coöperating abutments and a set of pins 41 carried by the wheel form a connection of variable effective length between the actuator lever 25 and the pawl lever 21.

In the present embodiment of the invention the wheel 43 is designed as a pattern mechanism to determine the length of the successive steps of the work carrier. Referring particularly to Fig. 2, it will be seen that the rim of the wheel is pierced with a series of holes to accommodate any suitable number of pins 41 and that if the wheel is rotated these pins will be presented in succession between the abutments 37 and 39. To effect this the wheel is urged in a counter clockwise direction (viewing Fig. 2) by a suitable frictional transmission device 45 which ordinarily would rotate it at a comparatively high speed. Means are provided for halting the wheel against the action of the friction drive so as to present successive pins between the abutments upon the successive strokes of the fixed throw actuator. In the present instance, this means takes the form of a spring pressed latch 47 which extends into the path of the pins, as shown in Fig. 2, and holds one of them in position between the abutments. To release the latch the block 33 has a nose portion 49 provided with a beveled end 51 arranged to coöperate with roll 53 on the latch. As the sleeve 33 completes its stroke to the left, viewing Fig. 1, the roll 53 will ride up the beveled surface 51 and the latch 47 will be moved clear of pin 41 and the wheel 43 will be released to the action of the frictional driving mechanism 45 as the sleeve commences

its return stroke. At the same time the latch 65 47 will drop down into position to engage the next pin which is set in the rim of the wheel and the latter is held in proper position to transfer motion from the abutment 39 to the abutment 37.

Viewing Fig. 2, it will be seen that I provide a cam member 55 coöperating with the left hand ends of the pins 41 for repositioning them with their heads in contact with the left hand side of the wheel ready for 75 presentation a second time when the wheel has made a revolution between the abutments.

The manner of using the machine can readily be understood from the description 80 of its structure. A suitable number of pins corresponding in length to the length of the successive steps between staples on the desired blank are selected and placed in position in the wheel 43 with the first in contact with the latch 47. As the main power shaft is rotated the stapler head will be reciprocated and in alternation the carrier pins will be moved through a series of steps whose length will depend directly upon the 90 length of pins in the pattern mechanism. The spacing of successive staples may therefore be controlled as desired. When one box blank is finished the friction drive of the wheel 43 will provide for turning it to a 95 zero position with the first pin of the series in contact with the latch 47. This feature is very desirable as it is possible to run the machine continuously and not be troubled about making adjustments for successive 100 blanks. At the same time a large pattern member or wheel 43 may be used with provision for accommodation of a number of pins equal to the number of staples in the largest size of blank and need not be 105 changed for smaller blanks wherein fewer staples are required.

The machine is positive in its action and has a strong and simple mechanism. No reliance is placed on springs and even the 110 spring of the latch 47 might be dispensed with as gravity would suffice to return the latch to position.

I have described in considerable detail the embodiment of the invention illustrated in 115 the accompanying drawing wherein I have shown it as applied to a wirebound box machine of that type wherein a work-holder in the form of endless chains is moved relatively to a fixed stapling mechanism. It 120 will be understood, however, that my purpose in making such a minute description was to render my invention more readily comprehended and that it is not limited to the details of structure shown and described. 125 On the contrary, the structure and the principles thereof may be widely varied without departing from the spirit of the invention.

What I do claim and desire to secure by Letters Patent is:

1. A machine for use in making wire-bound boxes comprising, in combination, means to secure binding wire to box parts; work-supporting means; means to cause relative progression between the work and the wire-securing means for fastening the binding wire at intervals; pattern means having devices corresponding to desired positions of fastenings on a piece of work; means to coöperate with the pattern means for controlling the progression; and automatic means to cause repeating coöperations of said pattern means and the last-named means for controlling the disposition of fastenings upon successive pieces of work.
2. A machine for use in making wire-bound boxes comprising, in combination, means to secure binding wire to box parts; work-supporting means; means to cause relative progression between pieces of work and the wire-securing means for fastening the binding wire at intervals; means including a set of controlling members for controlling the progression with respect to a piece of work; and automatic means to cause successive actions of said set with respect to each of successive such pieces of work.
3. A machine for use in making wire-bound boxes comprising, in combination, means to secure binding wire to box parts; work-supporting means; means to cause relative progression between pieces of work and the wire-securing means for fastening the binding wire at intervals; a set of controlling members; means coöperating therewith to control progression for controllably disposing fastenings for a piece of work; a moving means for presenting said members successively to the coöperating means; and means for operating said moving means to cause repeated presentations of said members to control the disposition of fastenings on successive such pieces of work.
4. A machine for use in making wire-bound boxes comprising, in combination, means to secure binding wire to box parts; work-supporting means; means to cause relative progression between pieces of work and the wire-securing means for fastening the binding wire at intervals; means including a set of successively-acting controlling members for controlling progression of a piece of work; and automatic means to cause repeated actions of said set to control the progression with respect to each of successive such pieces of work.
5. A machine for use in making wire-bound boxes comprising, in combination, means to secure binding wire to box parts; work-supporting means; means to cause relative progression between the work and the wire-securing means for fastening the binding wire at intervals; and automatic pro-

gression-controlling means including a set of controlling members, means to present said members for action sequentially in rotation, and means for controlling the successive presentations of the set.

6. A machine for use in making wire-bound boxes comprising, in combination, means to secure binding wire to box parts; work-supporting means; means to cause relative progression between the work and the wire-securing means for fastening the binding wire at intervals; pattern means corresponding to a desired disposition of fastenings for a piece of work; means to coöperate with the pattern means for controlling such progression; automatic means to cause repeating actions of the pattern means; and means for controlling each action.

7. A machine for use in making wire-bound boxes comprising, in combination, means to secure binding wire to box parts; work-supporting means; means to cause relative progression between the work and the wire-securing means for fastening the binding wire at intervals; pattern means corresponding to a desired disposition of fastenings for a piece of work; means to coöperate with said pattern means for controlling progression; a pattern carrier yieldably driven to cause operations of the pattern in rotation; and means for controlling each operation of the pattern.

8. A machine for use in making wire-bound boxes comprising, in combination, means to secure binding wire to box parts; work-supporting means; means to cause relative progression between the work and the wire-securing means for fastening the binding wire at intervals; a continuously yieldably driven revolving pattern means, having pattern devices corresponding to a desired pattern of fastenings; means for controlling its revolutions; and means coöperating with the pattern devices at each revolution for controlling the progression to position fastenings according to the pattern.

9. A machine for use in making wire-bound boxes comprising, in combination, means to secure binding wire to box parts; work-supporting means; means to cause relative progression between the work and the wire-securing means, including a motion-transmission mechanism; a pattern means having a set of controlling members corresponding to desired positions of fastenings; and means for successively introducing said controlling members into said transmission mechanism for controlling steps of the relative progression thereby.

10. A machine for use in making wire-bound boxes comprising, in combination, means to fasten binding wire to box parts; work-supporting means; and means to cause relative progression between the work and

the wire-securing means in steps of controlled length to locate fasteners at selected points on the work, including a motion-transmitting mechanism effective during 5 different phases of its operation and a series of controlling members determining by their lengths the phases of effectiveness of said mechanism.

11. A machine for use in making wire-bound boxes comprising, in combination, means to secure binding wire to box parts; work-supporting means; means to cause relative progression between the work and the wire-securing means, including a motion-transmission mechanism; a set of controlling members of lengths proportioned to desired fastening intervals; and means for introducing said members into said transmission-mechanism sequentially in rotation.

12. A machine for use in making wire-bound boxes comprising, in combination, means for securing binding wire to box parts; work-supporting means; a series of members of lengths proportional to a series 25 of desired fastening intervals; and means to cause relative step movements between the work and the wire-securing means including means for transmitting step movements through said members in succession.

13. A machine for use in making wire-bound boxes comprising, in combination, co-operating work-supporting, binding-wire applying and step-feed mechanisms to produce relative movements therebetween, in a continuously operating organization for wiring successive assemblies of box parts for successive boxes; and coöperating fastener-positioning means comprising a pattern-means for controlling said movements, 40 said pattern means having devices corresponding to desired positions of fastenings for an assembly of box parts, and operative means therefor causing action of said pattern means in rotation to control the positioning of fastenings for successive assemblies.

14. A box blank machine comprising, in combination, coöperating blank-feeding and binding-wire applying mechanism in a continuously operating organization for wiring successive blanks, and automatic fastener-positioning means including a set of feed-controlling members corresponding to a desired disposition of fastenings for a blank, 55 and means to cause operation of said set of members sequentially in rotation to control the positions of fastenings for a succession of blanks.

15. A machine for use in making wire-bound boxes comprising, in combination, binding-wire securing mechanism, and means to cause and control relative progression between said mechanism and work including a series of force-transferring members of different lengths and transmission means into

which said members are successively interposed to control the progression in accordance with their lengths.

16. A machine for use in making wire-bound boxes comprising, in combination, means to secure binding wire to box parts; work-supporting means for a succession of pieces of work; means for relatively moving the work and the wire securing means step-by-step for successive fastening operations; and automatic means to produce a skip feed to prevent a fastening operation between successive pieces of work, including a member in accordance with its length adapted to control a step movement, and automatic means to cause action of said member for said skip feed.

17. A machine for use in making wire-bound boxes comprising, in combination, means to secure binding wire to box parts; work-supporting means for a succession of pieces of work; means for relatively moving the work and wire securing means step-by-step for successive fastening operations; and automatic means to produce a skip feed to prevent a fastening operation between successive pieces of work, comprising a member independent of the work-supporting means and adapted to control a step movement; means yieldably urging said member toward an operative position, and controlling means to cause operative positions of said member at the time of the desired skip feed.

18. A machine of the class described comprising, in combination, fastener-setting mechanism; work-supporting means; means to cause relative step movements between the work and the fastener-setting mechanism including an actuating means of variable effective length and pattern-means having devices corresponding to a desired disposition of fastenings for controlling the effective length of said actuating means.

19. A machine of the class described comprising, in combination, fastener-setting mechanism; work-supporting means; a transmission mechanism for imparting relative step movements between the work and the fastener-setting mechanism; a set of members providing a pattern for fastenings; a carrier therefor in which said members are individually movably supported; and means for operating said carrier to interpose successively such members into said transmission mechanism as force transmitting members.

20. A machine for use in making wire-bound boxes comprising, in combination, a work holder for box materials, fastener-setting mechanism, and means to cause and control relative progression therebetween, including an actuator and a pattern of force-transferring members adapted to be automatically successively interposed between the actuator and the means moved.

21. In a machine of the class described, a feeding mechanism comprising a reciprocable driver arranged to impart motion on movement in one direction, a fixed throw actuator connected with said driver to position it at its extreme position in said direction and having provision for lost motion on movement in the opposite direction, a device carrying a plurality of abutment members of variable lengths and means to cause successive presentation of said members to govern the amount of such lost motion. 75
22. In a machine of the class described, a feeding mechanism comprising a reciprocable driver arranged to impart motion on movement in one direction, a fixed throw actuator, a plurality of force transmitting members, and means for interposing said members in succession between said actuator and driver to move the latter by the former. 80
23. In a machine of the class described, a feeding mechanism comprising a reciprocable driver arranged to impart motion on movement in one direction, a fixed throw actuator, means for positioning said driver in one extreme position, a plurality of force transferring members of different lengths, means to present them in succession in propelling relation to said driver and each with one end at the same fixed distance from said extreme position and means whereby said actuator will move each member to bring its other end to fixed distance from such position. 90
24. In a machine of the class described, a feeding mechanism comprising a reciprocable driver arranged to impart motion on movement in one direction, a portion movable therewith and having a fixed extreme position in one direction of movement, a reciprocating actuator having a coöperating portion having a fixed extreme position in the opposite direction and means for causing force transfer between said portions at different predetermined degrees of proximity. 105
25. In a machine of the class described, a feeding mechanism comprising a reciprocable driver arranged to impart motion on movement in one direction, a portion movable therewith and having a fixed extreme position in one direction of movement, an actuator having a coöperating portion having a fixed extreme position in the opposite direction, a plurality of force transferring members of different lengths and means for interposing the same in succession in operative position between said portions. 115
26. In a machine of the class described, a feeding mechanism comprising a reciprocable driver arranged to impart motion on movement in one direction, a fixed throw actuator, a telescopic connection therebetween, and means for varying the amount of telescoping movement on successive strokes of the actuator. 125
27. In a machine of the class described, a feeding mechanism comprising a reciprocable driver arranged to impart motion on movement in one direction, a fixed throw actuator, a connection therebetween of variable effective length and pattern mechanism for determining the effective length of the connection on successive strokes. 75
28. In a machine of the class described, a feeding mechanism comprising a reciprocable driver arranged to impart motion on movement in one direction, a rod extending therefrom, a member slidable back and forth on said rod and having a limited forward movement, and means for stopping said member against sliding movement on said rod at determined points in its forward stroke. 85
29. In a machine of the class described, a feeding mechanism comprising a reciprocable driver arranged to impart motion on movement in one direction, a rod extending therefrom, a member slidable back and forth on said rod and having a limited forward movement, and pattern mechanism for stopping said member against sliding movement on said rod at determined points in its forward stroke. 95
30. In a machine of the class described, a feeding mechanism comprising a reciprocable driver arranged to impart motion on movement in one direction, a fixed throw actuator arranged to move said driver to one extreme position and having provision for lost motion with respect thereto in the opposite direction, a pattern mechanism comprising a device having a plurality of projecting members of different lengths, latch mechanism for causing successive presentation of said members on strokes of the actuator, said members determining by their length the amount of lost motion permitted. 100
31. In a machine of the class described, and in combination, a conveyer for box materials, and means for intermittently moving said conveyer through the action of intermediary force - transferring members of different lengths, successively presented and moved distances varying with their lengths. 110
32. In a machine of the class described, a feeding mechanism comprising a reciprocable driver and a fixed throw actuator having spaced coöperating abutments, a carrier having a plurality of members of different lengths slidable therethrough and means for causing intermittent movement of said carrier to interpose said members in succession between said abutments. 120
33. In a machine of the class described, a feeding mechanism comprising a reciprocable driver and a fixed throw actuator having spaced coöperating abutments, a carrier having a plurality of members of different lengths slidable therethrough and means for causing intermittent movement of said carrier to interpose said members in succession between said abutments. 130

ferent lengths slidable therethrough and means for causing intermittent movement of said carrier to interpose said members in succession between said abutments and 5 means for returning said members to initial position after such interposition.

34. In a machine of the class described, a feeding mechanism comprising a reciprocable driver and a fixed throw actuator having spaced coöperating abutments, a carrier having a plurality of members of different lengths slidable therethrough, means for driving said carrier to bring said members between said abutments, latch means for 10 holding said members in position between said abutments and means for releasing said latch means on each stroke of the actuator.

35. In a machine of the class described, feeding mechanism comprising a reciprocable driver and a fixed throw actuator having coöperating abutments, a wheel, members slidably carried thereby and adapted for interposition longitudinally between said abutments on rotation of said wheel and 25 means for causing intermittent rotation of said wheel to effect successive presentation of such members.

36. In a machine of the class described, a feeding mechanism comprising a reciprocable driver and a fixed throw actuator having coöperating abutments, a wheel, members slidably mounted transversely of such wheel and adapted for interposition longitudinally between said abutments on 35 rotation of said wheel, means for causing intermittent rotation of said wheel to effect successive presentation of said members and means for normally positioning said members in extreme position on said wheel.

40 37. In a machine of the class described, a feeding mechanism comprising a reciprocable driver and a fixed throw actuator having coöperating abutments, a wheel, members slidably mounted transversely of such wheel and adapted for interposition longitudinally between said abutments on rotation of said wheel, means for causing intermittent rotation of said wheel to effect successive presentation of said members and a 45 cam surface adjacent said wheel for normally returning said members to and holding them in extreme position on said wheel.

38. In a machine of the class described, a feeding mechanism comprising a reciprocable driver and a fixed throw actuator having coöperating abutments, a wheel, members slidably mounted transversely of such wheel and adapted for interposition longitudinally between said abutments on rotation of said wheel, a friction drive for said wheel, a latch extending into the path of said members and means to release said latch on each stroke of the actuator.

39. A machine for use in making wire- 65 bound boxes comprising, in combination,

fastener-setting mechanism for applying binding wire to a succession of units of work progressively subjected to the action thereof; means to feed the work in steps of controlled length to locate fasteners where 70 desired thereon, including a pattern of feed controlling members for a unit of work adapted to operate uninterruptedly to control the feed movements of a succession of units of work and locate fasteners in each 75 unit according to said pattern.

40. A machine for use in making wire-bound boxes comprising, in combination, fastener-setting mechanism for applying binding wire to a succession of box blanks 80 progressively subjected to the action thereof; means to feed the box blanks in steps of controlled length to locate fasteners where desired thereon, including a pattern of feed-controlling members for a box blank adapted 85 to operate uninterruptedly to control the feed movements of a succession of box blanks and locate fasteners in each blank according to said pattern.

41. A machine for use in making wire-bound boxes adapted for continuous operation on materials for a plurality of boxes comprising, in combination, fastener-setting mechanism for applying binding wire to box parts progressively subjected to the action 95 thereof; work-forwarding means; and means to feed the work in steps of controlled length to locate fasteners where desired thereon, including a pattern of feed controlling members independent of the work-forwarding means.

42. A machine for use in making wire-bound boxes comprising, in combination, fastener-setting mechanism for applying binding wire to box parts progressively subjected to the action thereof; work-forwarding means; and means to feed the work in steps of controlled length to locate fasteners where desired thereon, including a pattern 105 of feed controlling members for a series of 110 units of work, said pattern being independent of the work-forwarding means.

43. A machine for use in making wire-bound boxes comprising, in combination, fastener-setting mechanism for applying binding wire to box parts progressively subjected to the action thereof; work-forwarding means; and means to feed the work in steps of controlled length to locate fasteners where desired thereon, including a pattern 115 of feed controlling members for a series of units of work, said pattern being independent of the work-forwarding means and adapted to control the feed movements of successive series of units of work and locate 120 fasteners in each series according to said pattern.

44. A machine for use in making wire-bound boxes comprising, in combination, fastener-setting mechanism for applying 130

binding wire to box blanks progressively subjected to the action thereof; work-forwarding means; and means to feed the work in steps of controlled length to locate fasteners where desired thereon, including a pattern of feed controlling members for a series of box blanks, said pattern being independent of the work-forwarding means.

45. A machine for use in making wire-bound boxes comprising, in combination, fastener-setting mechanism for applying binding wire to box blanks progressively subjected to the action thereof; work-forwarding means; and means to feed the work in steps of controlled length to fasteners where desired thereon, including a pattern of feed controlling members for a series of box blanks, said pattern being independent of the work-forwarding means and adapted 15 to control the feed movements of a succession of series of box blanks and locate fasteners in each series according to said pattern.

46. A machine for use in making wire-bound boxes comprising, in combination, fastener-setting mechanism; work-forwarding means; and a regulable feed mechanism for presenting selected fastener-receiving points on the work in fastener-receiving position, comprising a driver, an actuator therefor, and a pattern of force-transferring members for a unit of work adapted to be successively interposed between the actuator and the driver a plurality of times to control the feed movements of a plurality of units of work according to said pattern.

47. A machine for use in making wire-bound boxes comprising, in combination, fastener-setting mechanism; work-forwarding means; and a regulable feed mechanism for presenting selected fastener-receiving points on the work in fastener-receiving position, comprising a driver, an actuator therefor, and a pattern of force-transferring members for a series of units of work adapted to be successively interposed between the driver and the actuator a plurality of times to control the feed movements of a plurality of series of units of work according to said pattern.

48. A machine for use in making wire-bound boxes comprising, in combination, fastener-setting mechanism; work-forwarding means; and a regulable feed mechanism for presenting selected fastener-receiving points on the work in fastener-receiving position, comprising a driver, an actuator therefor, and a pattern of force-transferring members for a box blank adapted to be successively interposed between the driver and

the actuator a plurality of times to control the feed movements of a plurality of box blanks according to said pattern.

49. A machine for use in making wire-bound boxes comprising, in combination, fastener-setting mechanism; work-forwarding means; and a regulable feed mechanism for presenting selected fastener-receiving points on the work in fastener-receiving position, comprising a driver, an actuator therefor, and a pattern of force-transferring members for a series of box blanks adapted to be successively interposed between the driver and the actuator a plurality of times to control the feed movements of a plurality of series of box blanks according to said pattern.

50. A machine for use in making wire-bound boxes comprising, in combination, a work-support; fastener-setting mechanism; and means to cause relative progression between said mechanism and the work comprising a driver, an actuator therefor, and a series of force-transferring members adapted to be successively interposed between the actuator and the driver.

51. A machine for use in making wire-bound boxes comprising, in combination, a work-support; fastener-setting mechanism; and a regulable feed mechanism for causing progression between the work and the fastener-setting mechanism comprising a driver, an actuator therefor, and a series of variable-length, force-transferring members adapted to be successively interposed between the actuator and the driver and to determine by their lengths the extent of feed movements.

52. In a machine of the class described, a regulable feed mechanism comprising, in combination, a variable stroke driver adapted to uniformly initiate feed steps from the same position; an actuator therefor; and means for controlling the extent of movement of the driver.

53. A machine for use in making wire-bound boxes comprising; in combination, fastener-setting mechanism; means to cause relative progression between said mechanism and a work assembly in controlled steps of varied length to locate fasteners where desired in said work assembly; and means controlling said progression producing means to effect a like location of fasteners in a succession of work assemblies without interrupting the operation of the machine.

In testimony whereof I have signed my name to this specification.

CHARLES H. BOMBARDIE.
